UNITED STATES PATENT OFFICE.

EDWARD JOSLIN KINGSBURY, OF KEENE, NEW HAMPSHIRE.

AUTOMATIC DRILLING MACHINE.

Application filed March 28, 1922. Serial No. 547,892.

To all whom it may concern:

Be it known that I, EDWARD J. KINGSBURY, a citizen of the United States, residing at Keene, in the county of Cheshire, State of New Hampshire, have invented certain new and useful Improvements in Automatic Drilling Machines, of which the following is a description, reference being had to the accompanying drawing and to the figures of reference marked thereon.

My invention relates to new and useful improvements in automatic drilling machines.

An object of the invention is to provide a drilling machine of this character in which the drill spindle is normally held retracted by spring means and fed forward by a cam until a predetermined pressure is applied to the drill spindle, after which the pressure is slightly relieved until the drill has worked forward into the work being done when the predetermined pressure is again applied to the drill spindle.

Another object of my invention is to provide a drilling machine in which the rapid forward movement of the drill spindle is prevented as it breaks through the work and at the same time provides means for automatically returning the drill to its starting point after it has broken through the work and lock it in said retracted position.

A still further object of my invention is to provide a simple and effective mechanism adapted to accomplish the above results and having certain details of structure and combination of parts hereinafter fully set forth.

In the accompanying drawings—

Figure 1 is a side elevation of an ordinary vertical drilling machine, showing my invention applied thereto;

Fig. 2 is an enlarged side elevation of the drill feeding and controlling means;

Fig. 3 is a horizontal sectional view of Fig. 2;

Fig. 4 is a side elevation, partly in section, of a modified form of my drill feeding and controlling mechanism; and

Fig. 5 is a top plan view of Fig. 4.

Referring now to the drawings, 1 represents the base of an ordinary vertical drilling machine having a housing 2, in which is arranged a vertical shaft 3, driven by a motor, or in any desired manner. The upper end of the housing has a forwardly extending arm 4, in which is rotatably

mounted the drill spindle 5. The spindle 5 is also longitudinally movable, so that the drill may be fed forward, all of which is well understood. Carried by the drill spindles are the pulley wheels 6, 7 and 8, over any one of which the belt 9 is adapted to pass, so that the rate of rotation of the drill may be varied by placing the belt on the different pulleys. The shaft 3 likewise has three pulleys 10, 11 and 12, over any one of which the belt 9 is adapted to be placed to correspond with the pulleys on the drill spindles. The arm 4 has a standard 13, to the upper end of which is pivotally connected the lever 14 at 15. This lever has a vertically adjustable screw 16 pivotally mounted therein and at its lower end has a universal joint connection with the upper end of the drill spindle 5, so that the spindle may be adjusted and is free to rotate and the lever 14 is free to swing on its pivot without causing any binding of the drill spindle.

Carried by the housing 2 is a boss 16' having an outwardly extending stud 17, upon which is rotatably mounted a sleeve 18, which has integral therewith an outwardly extending arm or lever 19, having a laterally turned end 20 through which loosely passes the rod 21. The rod 21, as shown in Fig. 1 of the drawings, is rigidly supported by the base 1 of the machine, and surrounding this rod, above the lever 19 and bearing upon the upper face thereof, is a coil spring 22. Loosely fitting upon the rod above the spring is an enlarged washer 23, against which the spring bears. Screwed upon the rod, above the washer, are the lock nuts 24 for holding the washer in place on the rod and also for varying the tension of the spring 22, as will be hereinafter more fully described.

Carried by the lever 19, intermediate the spring and its pivoted end, is a stud 25, 100 which is rotatably mounted in the lever and carries an enlarged friction grooved wheel 26 which frictionally engages the small grooved wheel 27 keyed upon the shaft 28, and which is continuously driven 105 by any desired means, off of the drill rotating shaft 3, or by any other desired means, it being understood that this wheel 27 must rotate continuously as long as the drill is rotating and operating. By this structure, 110 it will be seen that the large friction wheel 26 is held down upon the small wheel 28

by the spring 22, and is continuously rotat-
ing.

Pivotedly mounted upon the outer end of
5 the stud 17, intermediate its ends, is a lever
29. The outer end of the lever 29 is pivot-
ally connected at 30 to the rod 31 which
10 extends upwardly and its upper end is pivot-
ally connected at 32 to the lever 14, so that
the longitudinal movement of the drill spin-
dle in both directions is controlled, as will
15 be later described. The lever 29, beyond its
pivot 30, has connected thereto a coil spring
33, with its lower end connected at 34' to
the base 1, so that the tendency of the
20 spring is to draw that end downwardly and
throw the outer end upwardly and raise the drill spindle. The lever 29 adjacent its pivot has an enlarged downwardly
25 extending portion 34 which carries a pivot
35 upon which is rotatably mounted a roller
35' which engages the outer periphery of the cam 36 rigidly secured to the outer
face of the friction grooved wheel 26. The
roller, as shown, is below the cam and the
30 spring 33 at all times holds the same up-
wardly in engagement with the cam. The
cam 36 has a number of cam faces 37, 38,
39 and 40 arranged at different points
35 around its periphery, each cam face being
different for the different character of work
upon which the drill may operate, so that
the movement of the drill spindle in a longi-
tudinal direction is controlled.

Carried by the enlarged portion 34 of
35 the lever 29 is a pivoted dog 41, having a
notched lower end 42 adapted to engage the
spring pressed latch 43 held in engagement
with the dog 41 by means of a coil spring
43', and after the lever has traveled up-
40 wardly under the tension of the spring 33,
the dog catches on the latch 43 and the arm
is held raised so that the drill spindle can-
not be again forced down by the cam until
the latch is released.

45 In operation the small wheel 27 is con-
tinuously rotating and the spring 22 holds
the large wheel 26 downwardly in contact
therewith and frictionally drives the same.
The tension of the spring 33 holds the drill
50 up and at the same time holds the roller
35' in engagement with the cam 36. As the
drill cuts its way through the work the cam
is slowly rotating, forcing the lever 29
55 downwardly through the roller 35' and
feeding the drill forward. When the drill
strikes the work the downward movement
of the spindle will be resisted and the cam
roller is held against further movement.
The cam at this position has the up-slope
60 bearing against the roller and has the force
of the friction drive between the wheels
26 and 27, tending to revolve it. This will
cause the cam to climb up on the roller 35'
and the wheel 26 carried thereby to move
65 up and slightly separate the wheels 26 and

27 and thus cause a slipping action between
the same. The full force of the spring 22
is then imparted to the cam roller and
70 thence through the lever 29 and rod 31
to the drill spindle. This pressure feeds
the drill into the work and as the drill
punctures the work the cam roller 35' drops
75 and also the cam which allows the wheels
26 and 27 to engage and again start the
cam revolving. The climbing action of the
cam on the roller 35' is very slight, but it
is sufficient to raise the wheel 26 from 27,
80 so that the full force of the spring 22 is
imparted to the drill spindle. This action
is very rapid and in close succession so that
the actions almost appear continuous. The
maximum feed is controlled by the speed
85 of the drive wheel 27 and the slope of the
cam.

In the modification shown in Figs. 4 and
85 5, a beveled gear wheel 44 is mounted upon
a shaft corresponding to the shaft 28 and
is continuously rotated. This gear meshes
90 with a beveled gear 45, removably screwed
upon the lower end of the sleeve 46. This
sleeve has a flange 47 at its upper end which
95 rests upon the upper face of the support 47'
carried by the frame of the machine, and the
sleeve is rotatably supported yet held
against vertical movement. The upper end
100 of the bore of the sleeve is slightly conical
at 48, into which fits the clutch member 49,
so shaped as to closely fit the bore of the
sleeve. The clutch member 49 has a recess
105 50 in its upper end, in which is arranged
a ball 51, and a member 52 engaging the
ball and normally held down on the same
by a spring 53, and its upper end bears
110 against an adjustable screw 54, carried by
the frame of the machine, so that the sleeve
46 and the clutch member 49 are held in
frictional engagement and the member 49
115 driven by the sleeve.

Connected to the rod 55, which corre-
120 sponds to the rod 31 in the preferred form,
is a lever 56 which is pivoted at 57 and
provided with a spring 58 which normally
holds the lever up and raises the drill from
the work. The lower end of the member
115 49 extends beyond the sleeve 46 and the
beveled gear 45 and has keyed thereon a
cylindrical sleeve 59, having a cammed lower
edge 60 engaged by a roller 61 carried by
the lever 56. A latch 62 operated in the
120 same manner as that shown in my preferred
form, is carried by the lever 56, and needs
no further description.

In operation, it will be seen that the gear
44 is continuously operating, which in turn
125 continuously rotates the bevel gear 45 and
its sleeve. Through the conical recess and
tapering clutch member 49, the clutch mem-
ber is rotated causing the cam sleeve 59 to
rotate and the cam face engaging the roller
130 61 slowly forces the lever 56 downwardly

and thus feeds the drill. When the desired pressure is on the drill the cam sleeve 59 will climb up on the wheel and slightly raise the clutch member 49 and prevent its 5 rotation or its being driven by the sleeve 46. The moment the drill works forward, the clutch member again drops in engagement with the sleeve and the pressure is applied to the drill through the rotation of 10 the cam sleeve.

Having thus described my invention, what I claim as new and desire to secure by Letters Patent, is:

1. A drilling machine comprising a rotary 15 drill spindle, means for feeding the drill spindle forward, automatic means for stopping the feeding means when the drill stops its forward movement and brings spring pressure on the drill spindle, and automatic 20 means for bringing the feeding means into operation when the drill spindle has moved forward under spring pressure.

2. A drilling machine comprising a rotary 25 drill spindle, a cam for feeding the drill spindle forward, automatic means for stopping the cam when the drill stops its forward movement to bring a spring pressure on the drill spindle, and automatic means 30 for starting the cam after the drill spindle has moved forward under the spring pressure to restore the cam feed.

3. A drilling machine comprising a rotary 35 drill spindle, a lever for feeding the drill spindle forward, a spring pressed arm, a rotating cam carried by the arm and engaging the lever for feeding the drill forward, and automatic means for stopping the rotation of the cam when the drill stops moving forward and causing the spring arm 40 to exert pressure on the drill spindle, and automatic means for starting the rotation of the cam when the drill spindle has moved forward under the pressure of the spring arm.

4. A drilling machine comprising a rotary 45 drill spindle, a lever for feeding the drill spindle forward, a roller carried by the lever, a spring pressed arm, a frictionally driven cam carried by the arm and engaging the roller carried by the lever, and feeding the drill spindle forward, automatic means for stopping the rotation of the cam when the drill stops moving forward and causing the spring arm to exert pressure on the drill spindle, and automatic means for starting the rotation of the cam when the drill spindle has moved forward under pressure of the spring arm to restore the cam feed.

5. A drilling machine comprising a drill 55 spindle, a frictionally driven cam, a lever for feeding the drill spindle forward, a roller carried by the lever and engaged by the cam, said cam being adapted to climb up on the roller when the drill is not feeding for-

ward and disengage the friction drive and automatically restore the friction drive when the drill has moved forward.

6. A drilling machine comprising a rotary 70 drill spindle, a cam for feeding the drill spindle forward, automatic means for causing the cam to maintain a predetermined even pressure on the drill spindle for feeding it forward, and automatic means for stopping said cam feed when the drill 75 is not properly moving forward.

7. A drilling machine comprising a rotary 80 drill spindle, a cam for feeding the drill spindle forward, automatic means for causing the cam to maintain a predetermined even pressure on the drill spindle for feeding it forward, and automatic means for relieving the pressure of the cam when the drill is not moving forward and restoring the pressure when the drill has again 85 moved forward.

8. A drilling machine comprising a rotary 90 drill spindle, a cam for feeding the drill spindle forward, and an automatic friction drive for said cam for maintaining a predetermined even pressure on the drill spindle when it is moving forward.

9. A drilling machine comprising a rotary 95 drill spindle, a cam for feeding the drill spindle forward, and an automatic friction drive for said cam for maintaining pressure on the drill spindle when the drill is moving forward and relieving said cam pressure when the drill ceases to feed forward and to restore said pressure when the 100 drill again moves forward.

10. A drilling machine comprising a rotary 105 drill spindle, a lever for feeding the drill forward, a spring connected to the lever for holding the drill in its retracted position, a cam engaging said lever for feeding the drill spindle forward, and automatic means for causing the cam to maintain a predetermined even pressure on the lever for feeding the drill forward at an even 110 pressure.

11. A drilling machine comprising a rotary 115 drill spindle, a lever for feeding the drill spindle forward, a spring connected to the lever for holding the drill in its retracted position, a cam engaging said lever for feeding the drill spindle forward, and an automatic friction drive for said cam for maintaining a predetermined even pressure on the lever for feeding the drill forward.

12. A drilling machine comprising a rotary 125 drill spindle, a lever for feeding the drill spindle forward, a spring connected to the lever for holding the drill in its retracted position, a cam engaging said lever for feeding the drill spindle forward, an automatic friction drive for said cam for maintaining a predetermined even pressure on the lever for feeding the drill forward and relieving said pressure when the drill is not 130

feeding forward and restoring the pressure on the drill spindle when it moves forward.

13. A drilling machine comprising a rotating drill spindle, a lever connected to said spindle for feeding it forward, a pivoted spring pressed arm, a friction drive wheel mounted on the arm, a continuously driven wheel in engagement with the friction drive wheel, a roller carried by the lever, a cam carried by the friction drive wheel and normally held in engagement with the roller carried by the lever, whereby the lever is forced down by the cam until the drill stops its forward movement which causes the cam to climb on the roller and stop the friction drive of the cam and brings the spring arm pressure on the drill to feed it forward until the friction drive is again brought into action to cause the cam drive to feed the drill forward.

14. A drilling mechanism comprising a rotating drill spindle a lever connected to the said spindle for feeding it forward, a pivoted spring pressed arm, a continuously driven wheel in engagement with the friction drive wheel, a roller carried by the lever, a cam carried by the friction drive wheel and normally held in engagement with the roller carried by the lever whereby the lever is forced down by the cam until the drill stops its forward movement which causes the cam to climb on the roller and stop the friction drive of the cam and brings the spring arm pressure on the drill to feed it forward until the friction drive is again brought into action to cause the cam drive to feed the drill forward.

In testimony whereof, I affix my signature.

EDWARD JOSLIN KINGSBURY.
